VENETIAN BLIND HEAD-BAR ASSEMBLING
DEVICE

Harry Nelson, New York, N. Y., assignor to
Lorentzen Hardware Mfg. Corp., New York,
N. Y., a corporation of New York

Application December 5, 1946, Serial No. 714,211

9 Claims. (Cl. 153—39)

1

This invention relates to the assembly of Venetian blinds and more particularly to a tool for applying braces to the free longitudinal edges of channel-shaped metal Venetian blind head bars.

Channel-shaped metal head bars are frequently employed in the construction of Venetian blinds. It is advantageous to make such head bars from relatively light gauge metal, not only for economy and for convenience in shaping and cutting the head bars, but also for ease in handling the finished blinds. Such head bars are often provided with inwardly turned, open, longitudinal beads along the free edges of the channel, these beads serving to finish the channel off smoothly and reinforce the edges. It has been found desirable to reinforce the channel by means of transverse braces extending between the free edges of the channel. One centrally-located brace will suffice for a short head bar, but usually two or more braces are positioned at intervals along the length of the head bar. Each brace has hooked ends which are adapted to be interlocked with the beads of the channel. One style of brace that has proved satisfactory is formed of a strip of relatively soft metal which is provided with hooked ends. The strip constituting the brace is so shaped that, prior to installation, it extends upwardly and then downwardly forming an inverted V. The hooked ends of the brace are adapted to be inserted into the beads of the channel, after which the brace is reshaped, preferably in such fashion as to straighten the brace. The reshaping rocks the hooked ends of the brace, causing them to interlock with the beads and establish a rigid connection between the free edges of the channel and the brace. Braces and channels of the type being considered are also disclosed in my copending application Serial No. 601,671, filed June 26, 1945 and issued November 30, 1948 as Patent 2,455,135.

The tool of the present invention is particularly intended for applying braces such as above described to channel-shaped metal Venetian blind head bars. In the form disclosed, this tool includes a base which is provided with flanges which extend outwardly and then downwardly, these flanges being adapted for engagement with the sides of the channel-shaped head bar to retain the base in operating position thereon. An anvil projects centrally from one end of and slightly below the level of the base, the anvil being designed to be inserted immediately beneath the final position of the brace to be applied. A lever is mounted for oscillation on the base, the lever

2

including a pressure-applying portion or hammer arranged to move toward the anvil upon operation of the lever. The lever is normally retained in raised position by a spring, in which position the hammer is widely separated from the anvil.

An object of this invention is to provide a tool for the easy and rapid installation of braces of the type described in Venetian blind head bars.

Another object of the invention is to provide a brace-applying tool that will maintain the brace in engagement with beads of the head bar while the brace is being reshaped to interlock it with the head bar.

An additional object of the invention is to provide such a tool that will quickly and positively position the brace at right angles to the length of the head bar.

A further object of the invention is to provide such a tool that will guide the ends of the brace into bead engaging position during the brace-applying operation.

A still further object of the invention is to provide such a tool that will so reshape a brace of the type described as to leave the brace straight after the pressure of the tool has been removed.

Still further objects of the invention are to provide such a tool which can be cheaply and easily manufactured, and which will be durable and serviceable in its operation.

Further objects and objects relating to details and economies of manufacture and use will more definitely appear from the detailed description to follow.

My invention is clearly defined in the claims. In the claims, as well as in the description, parts are at times identified by specific names for clarity and convenience, but such nomenclature is to be understood as having the broadest meaning consistent with the context and with the concept of my invention as distinguished from the pertinent prior art. The best form in which I have contemplated applying my invention is illustrated in the accompanying drawings forming part of this specification, in which:

45 Fig. 1 is a perspective view of the tool, the channel and brace being indicated.

Fig. 2 is a perspective view of a brace which may be applied to a head bar by means of the tool.

50 Fig. 3 is an edge elevation of the brace shown in Fig. 2.

Fig. 4 is a top plan view of the brace shown in Fig. 2.

Fig. 5 is a side elevation of the tool in position on a head bar, the brace being shown and a por-

tion of the channel being broken away to show details of construction of the tool.

Fig. 6 is a vertical cross section taken on the line 6—6 of Fig. 5, showing in end elevation the brace and tool in position for application of the brace to the head bar.

Fig. 7 is a view similar to Fig. 5, the brace being shown in secured position.

Fig. 8 is a vertical cross section taken on the line 8—8 of Fig. 7, the brace being shown in secured position on the head bar but before removal of the hammer pressure therefrom.

Fig. 9 is a vertical cross section through the head bar similar to Fig. 8, the tool having been removed.

Fig. 10 is a detailed vertical cross section showing the engagement of an end of the brace in a bead of the head bar before straightening the brace.

Fig. 11 is a detailed view similar to Fig. 10 after straightening of the brace.

For a complete understanding of the brace-applying tool, an understanding of the detailed construction of the head bar and the brace is first necessary. Referring to Figs. 1 and 6, a head bar 15 is formed of sheet metal and is of channel-shaped cross section. An open, inwardly turned, round longitudinal bead 16 is formed along each of the free longitudinal edges of the head bar 15. The metal of which the head bar 15 is formed may be corrugated if desired to increase the strength of the bar.

The brace 17, which is best seen in Figs. 2, 3 and 4, is formed of a rectangular strip of relatively soft metal such as mild steel, preferably having an inverted V-shape as shown in Fig. 3. Each end 19 of the brace is upwardly bent into hook shape, the hook formation including a small bend at transverse bending line 20 and further bending in the transverse zone 21. The ends of the brace 17 beyond the zones 21, 21 are substantially vertical to facilitate their insertion in the beads 16, 16 of the head bar 15. The relationship of size of the head bar 15 and the brace 17 is such that, when the intermediary portion 22 of the brace 17 is straightened, the distance between the bend zones 21, 21 will be approximately the distance across the open side of the head bar.

In the application of the brace 17 to the head bar 15 the ends 19, 19 of the brace are telescoped into the open beads 16, 16 of the head bar, the sides of the head bar being manually flexed toward each other as shown in Figs. 1 and 6. After engagement of the brace 17 with the head bar 15, the intermediary portion 22 of the brace is straightened, thus causing the hooked end portions 19, 19 of the brace to firmly interlock with the beads 16, 16 of the head bar as shown in Figs. 9 and 11. During the straightening of the brace, it is essential that the hooked ends 19, 19 be maintained within the beads 16, 16. The action of straightening the intermediary portion 22 of the brace 17 hooks the ends 19, 19 of the brace into firm interlocking engagement with the bead, thus resulting in a permanent attachment of the brace to the head bar that will firmly resist displacement.

The tool for applying the brace 17 includes a base 24 which may be formed as a rigid sheet metal stamping. At one end the base 24 has a pair of flanges 25, 25 which extends outwardly and then downwardly, and at the other end the base has a pair of similar flanges 26, 26. Each flange 25 is in alignment with a flange 26. The flanges 25, 25, as well as the flanges 26, 26, are so

spaced that the base 24 will span the open side of the head bar 15 as shown in Fig. 8, the flanges 25, 25 and 26, 26 projecting downwardly outside of the head bar. These four flanges may be outwardly inclined somewhat for ease of engagement of the tool with the head bar. An additional pair of depending longitudinal flanges 27, 27 is formed on the base 24 between the pairs of flanges 25, 25 and 26, 26, the flanges 27, 27 being spaced somewhat closer together than the other flanges, so that they will enter between the sides of the head bar 15 even when the head bar 15 is held in the somewhat collapsed condition shown in Fig. 6 prior to straightening the brace 17.

The base 24 is split at its forward end into two bifurcate portions 29 which are offset downwardly as shown. Together these portions form a generally horizontally projecting shelf or anvil 28 positioned a short distance below the level of the remainder of the base 24. The surfaces of the portions 29, 29 are slightly inwardly inclined so as to form a very flat V, as best shown in Figs. 6 and 8. In addition, the forward tips 30, 30 of the bifurcate portions 29, 29 are inclined downwardly somewhat as seen in Figs. 6 and 7 in order to facilitate introduction of the anvil 28 beneath a brace 17 to be applied to the head bar.

A channel 31 is secured to the top surface of the base 24 by spot welding or otherwise fastening the bottom 32 of the channel along the longitudinal center line of the base 24. A transverse pin 34 pierces the side walls 35, 35 of the channel 31, being held captive by cotter pins 36, 36 which pass through the ends of the pin.

A hand lever 37 is rotatably mounted between the legs 35, 35 of the channel 31, being journaled on the pin 34, and being arranged to be oscillated forwardly toward the anvil 28. The lever 37, which may be considered as a hammer or pressure-applying means, includes a rectangular block 39 through which the pin 34 passes. Attached to the upper forward surface of block 39 there is a second block 40, which is provided with a slightly rounded contour on its forward surface 41. The block 40 is so positioned that the surface 41 thereof will approach and contact, or nearly contact, the upper surface of the anvil 28, the rounded contour of the forward surface 41 then lying generally parallel to the upper surface of the anvil as shown in Fig. 8. The block 40 may be secured in position on the block 39 by a screw 38 passing through the block 39 and threaded-
ly engaged in a bore 43 of the block 40. An operating rod or handle 42 projecting from the upper end of the block 39 completes the lever 37. The rod 42 may be slightly rearwardly inclined at a point 44 between its ends for convenience of operation.

A tab 45, upwardly directed from the base 32 of the channel 31, is provided with a hole 46 near its upper end. This tab serves as an anchor for one end of a helical spring 47, the other end of the spring being attached to an eye 49 secured to the block 39. The spring 47 biases the lever 37 into normally raised position as shown in Figs. 1 and 5.

Preparatory to the operation of the above-described tool, a brace 17 is placed at the desired installation point along the head bar and the ends 19, 19 of the brace telescoped into the beads 16, 16 of the head bar, the sides of the head bar being manually flexed toward each other to permit the brace to be inserted. The brace-apply-

ing tool is then placed on the head bar a short distance from the brace 17, the marginal tabs 25, 25 and 26, 26 extending outside of the head bar and the marginal tabs 27, 27 extending within the head bar, the underside of the base 24 resting on the beads 16, 16 and the anvil 28 pointing toward the brace. After so positioning the tool, it is slid forwardly along the head bar to the position shown in Figs. 1, 5 and 6, the forward tips 30, 30 of the anvil 28 serving to force the brace 17 up firmly against the beads 16, 16 where it is maintained by the anvil. The vertical part of the bifurcate portions 29, 29 forming the anvil serves to adjust the brace 17 into position at right angles to the sides of the head bar 15 if it has not originally been placed in such position.

To interlock the brace 17 with the head bar 15, the lever 37 is oscillated forwardly and downwardly for a single stroke as indicated in Figs. 7 and 8. This is accomplished by the hand of the operator, the operation of the tool being facilitated if the other hand be placed on the rear portion 50 of the base 24. Oscillation of the lever engages the surface 41 with the intermediary portion 22 of the brace 17, forcing this portion downwardly on the anvil 28. Inasmuch as the anvil 28 is supporting the ends 19, 19 of the brace 17, the intermediary portion of the brace is straightened as indicated in Figs. 8 and 9, thus hooking the end portions 19, 19 of the brace into firm interlocking relationship with the beads 16, 16 of the head bar.

It has been found preferable to force the intermediary portion 22 of the brace 17 slightly below the straight position, as best shown in Fig. 8, so that when pressure on the brace is relieved the resilience of the metal will cause it to take the straight position shown in Fig. 9. For this purpose the anvil has a flat V-shape as above described.

After reshaping the brace 17 to applied position, as above described, the lever 37 is released and the tool retracted from engagement with the brace by sliding it back along the head bar 15, after which the tool may be removed.

I claim:

1. A tool for reshaping an initially-bent brace and simultaneously attaching the ends thereof to the sides of a channel-shaped metal Venetian blind head bar, said tool comprising a base plate, means for supporting said plate on the longitudinal edges of the head bar channel, an anvil projecting from one end of and generally parallel to and slightly below said plate and adapted to be positioned beneath a brace spanning the open side of the channel, and means mounted on said plate for forcing an intermediary portion of the brace towards the anvil to straighten the same and thereby secure the brace in the head bar.

2. A tool for reshaping an initially-bent brace and simultaneously attaching the ends thereof to the sides of a channel-shaped metal Venetian blind head bar, said tool comprising a base adapted to be supported by the longitudinal edges of the head bar channel and having downwardly projecting flanges to aid in maintaining it in temporary position on the channel, an anvil mounted on the base and adapted to be positioned beneath a brace spanning the open side of the head bar, and a cooperating pressure-applying member mounted for oscillation on the base and movable towards the anvil for reshaping an intermediary portion of the brace with resultant attachment of the ends of the brace to the sides of the channel.

3. A tool for reshaping an initially-bent brace and simultaneously attaching the ends thereof to

the sides of a channel-shaped metal Venetian blind head bar, said tool comprising a base adapted to be supported by the longitudinal edges of the head bar channel and having spaced downwardly directed projections to aid in maintaining it in temporary position on the channel, an anvil carried by the base and adapted to be positioned beneath a brace spanning the open side of the head bar, and a cooperating pressure-applying member connected with the base and movable towards the anvil for reshaping an intermediary portion of the brace with resultant attachment of the ends of the brace to the sides of the channel.

4. A tool for reshaping an initially-bent brace and simultaneously attaching the ends thereof to the sides of a channel-shaped metal Venetian blind head bar, said tool comprising an elongated base, each end of said base having a pair of flanges extending outwardly and downwardly and so spaced that the base will span the open side of the head bar with the flanges outside of the head bar, an additional pair of downwardly protruding flanges so positioned that they will enter between sides of the head bar, the forward end of said base being split into a bifurcated portion offset downwardly to form an anvil, the top surfaces of said portion being slightly inclined inwardly so as to form a very flat V, said anvil being adapted to be positioned beneath a brace spanning the open side of the head bar, a channel secured to the top of said base along its longitudinal center line, and a pressure-applying means pivotally mounted between the legs of said channel and arranged to be oscillated forwardly toward the anvil for reshaping an intermediary portion of the brace with resultant attachment of the ends of the brace to the sides of the channel.

5. A tool for reshaping an initially-bent brace and simultaneously attaching the ends thereof to the sides of a channel-shaped metal Venetian blind head-bar, said tool comprising a base adapted to span between the longitudinal edges of the head-bar channel, the base being provided with formations to aid in maintaining it in temporary position on the channel, an anvil mounted on the base and adapted to be positioned beneath a brace spanning the open side of the head-bar channel, and a lever mounted on the base and oscillatable towards the anvil for forcing an intermediary portion of the brace towards the anvil to straighten the same and thereby secure the brace in the head-bar.

6. A tool for reshaping an initially-bent brace and simultaneously attaching the ends thereof to the sides of a channel-shaped metal Venetian blind head-bar, said tool comprising a base adapted to span between the longitudinal edges of the head-bar channel, the base being provided with formations to aid in maintaining it in temporary position on the channel, an anvil mounted on the base and adapted to be positioned beneath a brace spanning the open side of the head-bar channel, and means mounted on the base for forcing an intermediary portion of the brace towards the anvil to straighten the same and thereby secure the brace in the head-bar.

7. A tool for reshaping an initially-bent brace and simultaneously attaching the ends thereof to the sides of a channel-shaped Venetian blind head-bar, said tool comprising a base adapted to span between the longitudinal edges of the head-bar channel, the base being provided with vertical formations fitting beside the edges of the head-bar channel to aid in maintaining the base in temporary position on the channel, an anvil

mounted on the base and adapted to be positioned beneath a brace spanning the open side of the head-bar channel, and means mounted on the base for forcing an intermediary portion of the brace towards the anvil to straighten the same and thereby secure the brace in the head-bar.

8. A tool for reshaping an initially-bent brace and simultaneously attaching the ends thereof to the sides of a channel-shaped metal Venetian blind head-bar, said tool comprising a base adapted to span between and be supported by the longitudinal edges of the head-bar channel and having spaced projections fitting beside each side of each longitudinal edge of the head-bar channel to aid in maintaining it in temporary position on the channel, an anvil carried by the base and adapted to be positioned beneath a brace spanning the open side of the head-bar, and a cooperating pressure applying member connected with the base and movable towards the anvil for reshaping an intermediary portion of the brace with resultant attachment of the ends of the brace to the sides of the channel.

9. A tool for reshaping an initially-bent brace and simultaneously attaching the ends thereof to the sides of a channel-shaped metal Venetian blind head-bar, said tool comprising a generally flat base adapted to span between and be supported by the longitudinal edges of the head-bar channel and having spaced projections fitting be-

5 side each side of each of the longitudinal edges of the channel to aid in maintaining it in temporary position on the channel, an anvil carried by the base and adapted to be positioned beneath a brace spanning the open side of the head-bar, and a lever pivotally mounted on the base and oscillatable towards the anvil for reshaping an intermediary portion of the base with resultant attachment of the ends of the brace to the sides 10 of the channel.
